United States Patent Office.

PETER A. STEWART, OF LUCESCO, PENNSYLVANIA.

Letters Patent No. 94,523, dated September 7, 1869.

IMPROVED GOVERNING-DEVICE FOR STEAM-ENGINES.

The Schedule referred to in these Letters Patent and making part of the same

To all whom it may concern:

Be it known that I, PETER A. STEWART, of Lugesco, in the county of Westmoreland, and State of Pennsylvania, have invented a new and useful Improvement in Governor for Steam-Engines; and I do hereby declare that the following is a full, clear, and exact description thereof, reference being had to the accompanying drawings, and to the letters of reference marked thereon.

The nature of my invention consists in so constructing a steam-chest of a steam-engine that the steam in the chest will act on a piston-head, and thereby so operate a valve in the steam-supply-pipe as that it will regulate the flow of steam into the steam-chest.

To enable others skilled in the art to make and use my invention, I will proceed to describe its construction and operation.

In the accompanying drawings, which form part of my specification—

Figure 1 is a side elevation of my improvement in governor for steam-engines.

Figure 2 is a longitudinal section of the same, when cut through at line *y* of fig. 3.

Figure 3 is a top view or plan of the same.

In the accompanying drawings—

A represents an ordinary steam-chest of the common slide-valve engine.

The chest *A* is provided with a chamber, *B*, in which is placed a piston, *C*, to the outer end of which may be attached jointed levers, for operating a valve placed in the steam-supply pipe. The dotted lines *x* will indicate the arrangement of the jointed levers with relation to the outer end of the piston *C*. The jointed levers can be, if so desired, attached to the ordinary "ball-governor" of the steam-engine.

D represents an opening in the end of the steam-chest for the steam of the slide-valve.

As the skilful mechanic will readily understand the construction of the several parts of my improvement from the foregoing description, and by reference to the accompanying drawings, I will therefore proceed to describe the operation of my invention, which is as follows:

The steam enters the steam-chest through the ordinary supply-pipe, and as it expands equally in all directions, will press or act on the end of the piston *C*, and will thereby force it into the chamber *B*, which will operate the jointed levers indicated at *x*, and thereby so operate the valve, or "ball-governor" to which they may be attached as to cause the governor-valve in the steam-pipe to close. But if the pressure of steam is not greater in force than is required, the piston *C* will be forced back by the action of the governor-balls, or by other device, and thereby open the valve in the supply-pipe, so as to admit a full supply of steam into the steam-chest *A*. The skilful mechanic will readily see that the action of the piston *C* on the jointed levers indicated at *x* will depend on the pressure of steam in steam-chest *A*, and also that the piston *C* can be easily forced back to its normal position by the ordinary "ball-governor," or by other mechanical contrivance, which I leave to the judgment of the skilful mechanic.

Having thus described the nature and construction of my improvement,

What I claim as of my invention, is—

The steam-chamber *B* and piston *C*, in combination with the steam-chest *A*, for operating a governor-valve in the steam-supply pipe, as herein described.

PETER A. STEWART.
